UNITED STATES PATENT OFFICE.

JOHN P. PACA, OF CANTON, OHIO, ASSIGNOR TO THE DIEBOLD SAFE & LOCK COMPANY,
OF CANTON, OHIO, A CORPORATION OF OHIO.

AUTOMATIC PRESSURE-SYSTEM LOCK.

Application filed June 16, 1926. Serial No. 116,334.

The invention relates to automatic means for preventing unauthorized operation of the pressure systems of safe and vault doors and the like, which are customarily left open 5 during the day.

Such safe and vault doors, usually require the operation of a pressure system in order to effect tight closure thereof for enabling the operation of the door lock bolts, and in 10 such a door it is impossible to operate the main locking bolts without first tightly closing the door by the operation of the pressure system.

In the past it has frequently occurred that 15 bank robbers have locked bank officials in a safe or vault during the perpetration of a bank robbery; and one object of the present invention is to prevent such an undesired closing and locking of the safe or vault door by 20 providing automatic means preventing the unauthorized operation of the vault door pressure system for closing the vault door, said means being automatically operative after each authorized opening of the vault 25 door, and said automatic pressure system locking means being rendered inoperative only by the use of key operated means, the key for which presumably shall always be in the possession of an authorized person.

30 By these means it is rendered impossible for bank robbers to herd one or more bank officials in a safe or vault whose door happens to be open upon the arrival of the bank robbers, and to close the safe or vault door by 35 the operation of the pressure system, thereby enabling the operation of the main bolts; since safe or vault door systems provided with the present improvements are positively locked against operation by any unauthorized 40 person excepting one who has surreptitiously obtained a suitable key for rendering inoperative the automatic pressure system lock.

A further and concurrent object of the invention is to provide positive means for preventing jamming of the pressure system mechanism by turning the pressure system 45 operating handle too far.

In pressure systems at present in use, the pressure system operating mechanism may be 50 jammed by only a slight turning of the operating handle beyond a certain point.

The foregoing and ancillary objects are

attained by the use of a construction and arrangement hereinafter described in detail and illustrated in the accompanying drawings forming a part hereof, in which—

Figure 1 is a front perspective view of a vault door provided with a pressure system and the present automatic lock therefor;

Fig. 2, a detached fragmentary top plan view of the automatic pressure system lock and portions of the pressure system and vault, some of the portions being in section; and

Fig. 3, an off-set sectional view thereof as 65 on lines 3—3, Fig. 2.

Similar numerals refer to similar parts throughout the drawings.

A vault door indicated at 1, is hinged in a usual manner as by the hinge mechanism 1^a 70 to the door frame 1^b, and is provided with a pressure system indicated generally at 2 and including preferably horizontal shafts 3 rotatable by rotation of the hand wheel 4 connected to the shafts in a usual manner by 75 suitable enclosed gearing 5 and 6 and stub shafts 7.

The ends of the shafts 3 are provided at 8 with cams 9 for cooperating with cam slots 10 in the cam housing 11 secured to the door 80 frame 1^b in a usual manner.

The cams 9 cooperate with the slots 10 upon operation of the pressure system by rotation of the handle 4 to apply pressure to the door and squeeze it home, so that the main lock 85 bolts not shown, are registered with their wedge blocks and may be operated by suitable manipulation of the main lock handle 12.

It is impossible to manipulate the main lock handle 12 and operate the main safe lock 90 bolts until the above described pressure system has been operated to tightly close the vault door.

In order to prevent unauthorized operation of the vault door pressure system, preferably the lower rotating shaft 3 is provided with an enclosed automatic lock, which automatically locks the whole pressure system mechanism when the same has been operated and the vault door opened.

For further operation of the pressure system, the use of a key by an authorized person as at 13 is required in order to render inoperative the automatic pressure system locking

means and enable rotation of the shafts 3 to apply the necessary pressure to the vault door for closing the same.

In other words, the shafts 3 are automatically locked against rotation whenever the vault door is open, and require the use of a key in order to operate the pressure system.

Each shaft 3 is provided near the swinging vertical vault door edge 14 with a bearing 10 through which the shaft extends and is journaled, and preferably the lower bearing 15 is provided with a centrally located aperture 16 extending from the door frame towards the lower shaft 3, and in which a plunger 17 is located.

The lower shaft 3 is provided with a socket 18, which registers with the aperture 17 when the pressure system has been operated for opening the vault door.

Between the plunger 17 and the vault door frame a compression spring 19 is located and the door frame end of the aperture 16 may be threaded and provided with a screw plug 20 for adjusting and maintaining the pressure of the spring 19 against the plunger 17.

Consequently when, by the operation of the pressure system for opening the vault door, the socket 18 in the lower shaft 3 has been registered with the aperture 16, the plunger 30 17 will be thrust into the socket 18 by the action of the spring 19, and will thereby lock the lower shaft 3 against rotation and prevent any movement of the pressure system operating handle 4 until the plunger 17 has been withdrawn from the socket 18.

For withdrawing the plunger 17 from the socket 18, the plunger 17 is provided with a slot 21 for operatively connecting the plunger with a rotatable arm 22 mounted upon the 40 inner shaft end of a paracentric key lock cylinder 23 and rotatable only by the turning of a suitable key inserted in the key slot 24 of the lock-cylinder.

The lock-cylinder is suitably mounted in the lower bearing 15 and secured therein as by means of the key screw 25, which prevents removal of the lock-cylinder.

The plunger 17 may be furthermore provided with a second guide slot 26 in which the inner end of a preferably vertical plunger screw guide 27 extends.

From the foregoing description, it is obvious that when the vault door is open, in order to operate the pressure system, it is necessary to insert a suitable key in the key slot 24 and to turn the same and withdraw the plunger 17 from the socket 18 in order to enable the shafts 3 to be rotated and the pressure system operated to tightly close the vault door.

Under usual conditions the pressure system is operated once a day at the close of business and the authorized person having charge of the locking of the safe will be provided with the key to fit the key slot of the

lock cylinder and release the automatic pressure system lock as aforesaid.

I claim:

1. In a vault door or the like, the combination of a pressure system for the door including a rotating shaft, a bearing for the shaft, there being an aperture in the bearing, and there being a socket in the shaft for registering with the aperture, a plunger in the bearing aperture, and means automatically moving the plunger into the shaft socket when the socket registers with the aperture. 70

2. In a vault door or the like, the combination of a pressure system for the door including a rotating shaft, a bearing for the shaft, there being an aperture in the bearing, and there being a socket in the shaft for registering with the aperture, a plunger in the bearing aperture, means automatically moving the plunger into the shaft socket when the socket registers with the aperture, and key operated means for withdrawing the plunger 75 from the socket. 80

3. In a vault door or the like, the combination of a pressure system for the door including a rotating shaft, a bearing for the shaft, there being an aperture in the bearing, and there being a socket in the shaft for registering with the aperture, a plunger in the bearing aperture, means automatically moving the plunger into the shaft socket when the socket registers with the aperture, and means for withdrawing the plunger from the socket. 90

4. In a vault door or the like, the combination of a pressure system for the door including stationary members and movable members including an operating shaft successively rotatable for operating the pressure system for permitting opening of the door and for operating the pressure system for permitting closing and locking of the door, and releasable means on one of the members operative independently of the position of the door for engagement with another member and automatically locking the shaft against further rotation after the shaft has been rotated to permit opening of the door. 100

5. In a vault door or the like, the combination of a pressure system for the door including stationary members and movable members including an operating shaft successively rotatable for operating the pressure system for permitting opening of the door and for operating the pressure system for permitting closing and locking of the door, releasable means on one of the members operative independently of the position of the door for engagement with another member and automatically locking the shaft against further rotation after the shaft has been rotated to permit opening of the door, and means for releasing the automatic locking means. 110

6. In a vault door or the like, the com- 120

bination of a pressure system for the door including an operating shaft successively rotatable for operating the pressure system for permitting opening of the door and for 5 operating the pressure system for permitting closing and locking of the door, releasable means operative independently of the position of the door and automatically locking the shaft against further rotation after the 10 shaft has been rotated to permit opening of the door, and key actuated means for releasing the automatic locking means.

7. In a vault door or the like, the combination of a pressure system for the door 15 including stationary members and movable members including an operating member successively movable for operating the pressure system for permitting opening of the door and for operating the pressure system for 20 permitting closing and locking of the door, and releasable means on one of the members operative independently of the position of the door for engagement with another member and automatically locking the movable 25 operating member against further movement after the member has been moved to permit opening of the door.

8. In a vault door or the like, the combination of a pressure system for the door 30 including stationary members and movable members including an operating member successively movable for operating the pres-

sure system for permitting opening of the door and for operating the pressure system for permitting closing and locking of the 35 door, releasable means on one of the members operative independently of the position of the door for engagement with another member and automatically locking the movable operating member against further movement 40 after the member has been moved to permit opening of the door, and means for releasing the automatic locking means.

9. In vault door or the like, the combination of a pressure system for the door including stationary members and movable members including an operating member successively movable for operating the pressure system for permitting opening of the door and for operating the pressure system for 45 permitting closing and locking of the door, and releasable means on one of the members operative independently of the position of the door for engagement with another member and automatically locking the movable 50 operating member against further movement after the member has been moved to permit opening of the door, and key actuated means for releasing the automatic locking means.

In testimony that I claim the above, I have hereunto subscribed by name.

JOHN P. PACA.
